CLAIM

I claim the ornamental design for a tail light guard, as shown and described.

DESCRIPTION

FIG. 1 is a front perspective view of the first embodiment of a tail light guard, showing my new design;

FIG. 2 is an end view thereof;

FIG. 3 is a front elevation view thereof;

FIG. 4 is a side view thereof;

FIG. 5 is a side view thereof opposite to that shown in FIG. 4;

FIG. 6 is a rear elevational view thereof opposite to that shown in FIG. 3;

FIG. 7 is an end view thereof opposite to that shown in FIG. 2; and,

FIG. 8 is a front perspective view of a second embodiment of a tail light guard, showing my new design, which is a mirror image of that shown in FIGS. 1-7.
